Primary Examiner — Rachel A. Voorhies(74) *Attorney, Agent, or Firm* — Perkins Coie LLP(57) **CLAIM**

The ornamental design for a display screen with graphical user interface, as shown and described.

DESCRIPTION

The sole FIGURE is a front view of a display screen with graphical user interface showing my new design.

The broken lines illustrate an electronic device with display screen and portions of a graphical user interface that form no part of the claimed design.
